MARINE SALVAGE DEVICE

Application filed April 22, 1929. Serial No. 357,065.

This invention relates to improvements in salvage and safety devices for marine vessels, and it has particular reference to devices of that character especially designed for use on 5 submarine vessels; it being the principal object of this invention to provide submarine vessels with manually and automatically releasable buoys designed to mark the location of a vessel in the event that it should become 10 disabled and sink, and also to attach the buoys by means of cables through which communication could be established with the occupants of the sunken vessel and also which would serve as pilot cables by means of which 15 55

grappling devices, at the ends of heavy hoisting or towing cables, could be easily and quickly attached to the vessel without the service of divers.

More specifically stated, the present invention resides in the provision of a salvage and safety device of the above character, including a housing that is permanently fixed within the hull or deck of a vessel and within which an air-tight buoy is releasably contained; the buoy being automatically releasable by outside pressure created incident to the vessel sinking below a predetermined depth, or it may be manually released from within the vessel, and it is designed after release to be discharged from its housing by compressed air, and on rising to the surface, to carry with it an attaching cable which serves as a pilot cable along which heavy grappling devices may be guided to and connected with the sunken vessel.

Another object of the invention resides in the novel construction of the grappling hook used with the salvage mechanism.

Other objects of the invention reside in the 40 various details of construction and in the combination of parts and in their mode of operation, as will hereinafter be described.

In accomplishing these objects of the invention, I have provided the improved details of construction, the preferred forms of which are illustrated in the accompanying drawings, wherein—

Figure 1 is a view illustrating the use of a 50 salvage device embodied by the present invention, for marking the location of a sunken

submarine vessel and also for the attachment of a pontoon thereto.

Figure 2 is an enlarged, sectional detail of the marking buoy as normally assembled within its housing; showing the attaching cable as wound on the reel within the buoy.

Figure 3 is a sectional detail of the grappling device as being lowered along the pilot cable for connection with the vessel.

Figure 4 is a sectional detail, illustrating 60 the manner in which the buoy is depressed within its housing to automatically effect the opening of an air valve and the resultant ejection of the buoy from the housing.

Referring more in detail to the drawings— 65

1 designates what may be a marine vessel with which the present device is used. As here illustrated, the vessel is of the submarine type, but it is to be understood that the present salvage device may be applied to any 70 kind of marine vessel and it is not intended that its use be limited to submarines, although it is believed that it is of greatest value to this type of vessel. Secured within the deck 2 of the vessel, is a housing 3 substantially of cylindrical form and having a somewhat restricted upper end, or neck portion, 3a that opens through the deck and which has an out-turned peripheral flange 4 through which rivets, or the like, 5 are extended to securely 75 fasten the housing within the vessel. A horizontal partition 6 divides the housing into upper and lower compartments 7 and 8, respectively; the latter compartment being relatively small and is designed to be used as a 80 chamber for compressed air which is delivered thereto from a source of supply through a supply pipe 9, this pipe being equipped with a control valve 10 which may be opened to charge the chamber and closed 85 to retain the charge. A pipe connection 11 continues from the supply pipe 9 into the upper chamber 7 of the housing, but a flow of compressed air from the lower chamber into the upper chamber is normally prevented by 90 means of a control valve 12 that is interposed within the pipe connection 11. The valve 12 is designed to be opened and closed by 95

rotative movement of a bell crank 13 that is fixed to the stem 14 of the valve.

Slidably fitted within the upper end, or neck portion, 3a of the housing 3, is a hollow, cylindrical buoy 18 of air-tight construction and which, within its lower end portion, rotatably supports a reel 19 on which a relatively small cable 20 of considerable length is wound. At its inner end, the cable is fastened to the reel and at its outer end is connected to one end of a heavy, metallic link 21 which, in turn, is fastened to a short length of heavy cable 22 that is coiled within the base of the compartment 7 and which, at its end, is permanently fastened by means of an eye bolt 23 to the partition wall 6 of the housing. Mounted slidably within an opening 26 through a side wall of the housing, is a slide 27 having a cam-like head 28 at its inner end against which a spring 29 that is disposed between the head and housing wall bears to urge the slide inwardly. The head 28 of the slide 27 is disposed in alignment below a curved, cam-like surface 30 at the lower end of the buoy, which is designed, as presently is apparent, to engage with the slide head when the buoy is depressed to thereby cause the head and slide to be moved outwardly.

Pivottally mounted on the outer end of the slide, is a bell crank 31 having a hooked arm 31a adapted to hook over the upper end of an arm 13a of the bell crank 13 that is fixed to the stem of the control valve 12; the arrangement being such that outward movement of the slide will operate to rotate and open the valve 12 to admit compressed air through the pipe connection 11 from the lower chamber 8 into the upper chamber 7, for the purpose of forcibly ejecting the buoy from the housing. If it should be desired to manually release the buoy 18, this may be done by the shifting of a lever 35 which has a notch 36 in its upper edge adapted to be interlocked with a hook 37 that is pivotally attached to a leg 31b of the bell crank 31 that is fixed to the outer end of the slide 27.

Assuming that the buoy and the housing are so constructed and assembled, should the vessel which is equipped with the device sink below the surface a predetermined distance, it is apparent that pressure of outside water against the upper end of the buoy 18 will force it inwardly, thereby bringing the cam surface 30 into contact with the head 28 of the slide 27 to push the latter outwardly and thereby automatically open the control valve 12 for the admittance of compressed air from the chamber 7 into the chamber 8 for the forcible ejection of the buoy. As soon as the buoy has once been discharged from its housing, it rises to the surface and, as it rises, the cable 20 unwinds from the reel 19. The buoy, since it is attached to the sunken vessel, serves to mark the location of the latter.

As the buoy rises to the surface, the cable 20 draws out the relatively short but heavy connecting cable 22 with which it is connect-

ed by means of the link 21. The link 21, as is presently described in detail, serves as a means for effecting connection of a grappling device used in raising the vessel. The link, as shown in Figure 3, is equipped with a conically tapered head end 24 and this is provided, at its apex, with an opening 24a within which the cable 20 is attached and, at its base, the head portion 24 has an encircling, undercut shoulder 25.

It is intended also that the buoy be equipped with an electric light 40 and that there be red glass lenses 41 mounted in openings 42 in the side walls of the buoy through which the light may be visible to attract attention to the buoy. The buoy attaching cable 20 also would contain circuit wires through which telephone communication might be carried on between occupants of the sunken vessel and those of a rescue vessel. Electric current for the lamp in the buoy might be provided through circuit wires carried within the cable 20 and having connection with an outlet 44 in the housing with which a source of electric current could be attached.

For the purpose of automatically opening the valve 13 by water pressure in the event that water should enter the sunken vessel, I have provided a cylinder 50 attached to the housing 3 and in which a piston 51 operates. A piston rod 52 extends outwardly from the closed upper end of the cylinder for engaging an arm 13b of the bell crank 13 to open the valve 12.

Assuming that the vessel sinks and that the buoy has been released and ejected and has risen to the surface, the cable 20 for attaching it will then serve as a pilot cable along which a grappling device may be lowered and connected with the link 21 for raising the sunken vessel. The preferred form of grappling device is shown in Figure 3 and it consists of an upper end yoke 59 to which a heavy hoisting cable, as at 60 in Figure 1, may be attached. To the end portions of the yoke, two or more downwardly extended, hook-like fingers 63 are pivotally connected. A spring 65 is attached at its ends to the fingers and draws them inwardly toward each other. The grappling hook is applied about the pilot cable by passing the latter through an eye 66 in the yoke and a guide 67 that is formed between the lower end portion of the fingers. The cable serves as a guide on which the grapple may be lowered over the conical head 24 of the link 21 and, as the fingers 63 pass downwardly over the head, their hook-like lower end portions 63a will snap beneath the undercut shoulder of the head and form a substantial connection between the hoisting cable and the cable 22.

With several of such hoisting cables connected with the vessel in the manner described, it is readily apparent that the vessel

can be raised sufficiently for towing it. Pontoon 70, as shown in Figure 1, might be used for supporting the vessel and it would be preferred that the towing cables pass through tubes 71 in the pontoons and be connected at their ends with cleats or posts 72 mounted on the top of the pontoon.

In the construction of the buoy and the housing, care would be taken to insure against leakage and it would be preferred that rubber packing rings, as at 75, be fitted in the buoy to prevent leakage between the latter and the neck portion of the housing within which it is fitted. It is also apparent that various details of construction in the valve mechanism and the means for opening and closing it could be made without departing from the spirit of the invention and, for this reason, it is not desired that the claims be limited only to the details herein shown.

Should it be desired to disconnect the arm 31a of the bell crank 31 from the arm 13a of bell crank 13, so as to prevent operation of the device during ordinary diving operations, this is easily done by drawing the hook 37 to the dotted line position of Figure 2.

Devices of this character may be made in various sizes and if sufficiently large may be equipped with manholes, as at 80, with suitable removably mounted closures 81, through which escape may be made or articles delivered into or from the vessel.

Having thus described my invention, what I claim as new therein and desire to secure by Letters-Patent, is:

1. In a marine vessel, a housing, a buoy releasably and movably contained therein, means rendered active by inward depression of the buoy incident to external pressure thereagainst for ejecting the buoy from the housing, and a cable connection between the buoy and the housing.

2. In a marine vessel, a housing, a buoy releasably and movably contained therein, means rendered active by inward depression of the buoy beyond normal position for ejecting the buoy from the housing, a section of hoisting cable having one end attached to the vessel, a buoy anchoring cable attached at its ends to the buoy and to the free end of said section of hoisting cable to draw out the latter incident to ejection of the buoy for attachment of a grapple thereto.

3. In a marine vessel, a housing fixed thereto and having an opening, a buoy contained within the housing and movably fitted in the opening, means releasable incident to certain depression of the buoy within the housing to effect a forcible ejection of the buoy, a section of hoisting cable contained within the housing and having one end fixed thereto, a link attached to the free end of said cable, an anchoring cable for the buoy attached to the free end of said link and whereby the hoisting cable will be drawn out incident to

rise of the buoy after ejection, and a grapple adapted to follow along the anchoring cable into an interlocked connection with said link.

4. In a marine vessel, an air-tight housing having an opening, a buoy fitted in said opening to be ejected by application of pressure medium within the housing, a source of compressed fluid medium connected with the housing, a control valve in the connection and means operable incident to depression of the buoy in the housing to open said valve.

5. In a marine vessel, an air-tight housing having an opening, a buoy fitted in said opening to be ejected by application of pressure medium within the housing, a source of compressed fluid medium connected with the housing, a control valve in the connection and means operable incident to depression of the buoy in the housing to open said valve, and a buoy anchoring cable attached at its ends to the buoy and to a part attached to the housing.

6. In a marine vessel, an air-tight housing having an opening, a compartment for compressed air formed within the housing, a buoy movably fitted within the opening of the housing, a connection through which compressed air may be admitted from the compartment into the housing to effect a forcible ejection of the buoy, a valve in said connection, means operable incident to depression of the buoy by external pressure to open said valve and an anchoring cable within the buoy having connection at its ends with the buoy and with the housing.

7. In a marine vessel, a buoy housing having an opening, a buoy slidably fitted in said opening to move inwardly under outside pressure and adapted to be ejected by the application of fluid pressure medium within the housing, a cable for anchoring the buoy to the vessel, a source of pressure medium connected with the housing, a valve in the connection, a slide in the housing disposed to be engaged and moved by the buoy incident to inward movement of the latter and means operable by movement of the slide to open the valve to admit pressure medium to the housing to eject the buoy.

8. In a marine vessel, a buoy housing having an opening, a buoy slidably fitted in said opening to move inwardly under outside pressure and adapted to be ejected by application of fluid pressure medium within the housing, a source of pressure medium connected with the housing, a valve in the connection, a valve actuating lever, a slide mounted in the housing and having an inner end portion adapted to be engaged by the buoy incident to inward movement of the latter to thereby move the slide outwardly, means on the slide for engaging the valve lever to open the valve by outward movement of the slide and a cable normally contained

within the buoy and connecting the latter with the housing.

9. In a marine vessel, a buoy housing having an opening, a buoy slidably fitted in said opening to move inwardly under outside pressure and adapted to be ejected by application of fluid pressure medium within the housing, a source of pressure medium connected with the housing, a valve in the connection, a valve actuating lever, a slide mounted in the housing and having an inner end portion adapted to be engaged by the buoy incident to inward movement of the latter to thereby move the slide outwardly, means on the slide for engaging the valve lever to open the valve by outward movement of the slide, a reel within the buoy, an anchoring cable wound on the reel and having one end connected thereto, a short length of hoisting cable in the housing and connected at one end thereto, a link attached to the free end of said hoisting cable having an enlargement to which the reel anchoring cable is attached; said hoisting cable being adapted to be drawn out by the buoy anchoring cable and the latter being adapted to serve as a pilot for guiding a grapple into an interlocked connection with the enlargement of the link.

10. In a marine vessel, an air-tight housing having an opening, a buoy slidably fitted in said opening to be moved inwardly by external pressure and to be ejected by application of pressure medium within the housing, a source of compressed fluid medium connected with the housing, a valve in the connection, a slide movable incident to inward movement of the buoy in the opening, a cylinder, a piston in the cylinder movable incident to external pressure, a manually shiftable element and a valve control means operable by the slide or by the manual means or by the piston, to open the valve.

Signed at Tacoma, Washington, this 10th day of April, 1929.

FRANK G. PRESTON.
